(57) **CLAIM**

The ornamental design for a reader device, as shown and described.

DESCRIPTION

FIG. 1 illustrates a top view for a reader device.

FIG. 2 illustrates a bottom view for the reader device.

FIG. 3 illustrates a front view for the reader device.

FIG. 4 illustrates a side view for the reader device.

FIG. 5 illustrates a side view for the reader device; and,

FIG. 6 illustrates a back view for the reader device.

The broken line showing portions of the reader device illustrates an unclaimed environment and forms no part of the claimed design. The claimed reader device is not intended to be limited to the scale illustrated in the figures.

1 Claim, 6 Drawing Sheets
